JOSEPH J. WASSER, OF ST. LOUIS, MISSOURI, ASSIGNOR TO PEVELY DAIRY COMPANY,
OF ST. LOUIS, MISSOURI, A CORPORATION OF MISSOURI

DISPLAY DEVICE

Application filed December 18, 1930. Serial No. 503,143.

This invention relates to display devices; and has special reference to display devices constructed and designed and adapted so that they may be easily passed over the upper ends of the present commercial milk bottles and seated upon the curved shoulders of the bottles in position to display any advertisements contained on the display devices.

This application is a continuation in part 10 of my copending application Serial No. 306,887, filed September 19, 1928.

It is a familiar fact, and a condition which is herein emphasized, that the present type of commercial milk bottle has an approximately cylindrical body provided with a tapering portion below its upper end and the upper end of which tapering portion, at approximately the smallest diameter thereof, merges and unites integrally with a circumferential flange or bead surrounding the open end of the bottle neck. This bead is of larger diameter than the adjacent portion of the bottle neck but is of less diameter than the body of the bottle.

Dairy products that are now sold and delivered by dairy companies to individual customers have become numerous and diversified to such an extent that the milk and cream delivered in these milk bottles constitute only 20 a small percentage of the dairy products sold and distributed by the dairy companies, although the milk and cream constitute a staple product that is delivered daily to a very large number of individual customers. The 25 milk and cream are delivered in these milk bottles usually at the doors of individual customers and the problem of advertising the various and diversified additional products has become and has long been a problem of the 30 dairy industry. It is desirable to advertise the various and diversified dairy products without subjecting the industry to burdensome or prohibitive expense, as by communications sent through the mails to the individual customers.

An object of the present invention is to provide a display device designed and constructed and adapted so that it may be passed over the relatively large circumferential flange at the upper end of the bottle neck and caused to engage against the tapered portion of the upper end of the bottle and thus support the display device for the most part above the cylindrical body of the bottle and around the tapered portion thereof and below said flange. The display devices are preferably made of paper for reasons of economy and must be constructed and arranged so that the display devices can be sold and distributed to dealers in flat condition 50 and may be assembled with the ends of the display devices attached so as to provide approximately conical display devices constructed in proportion, so that the display devices may be passed downwardly over the 55 flange at the end of the bottle neck without tearing the paper, and then seated upon the tapered portion of the bottle. The preferred construction comprises an arcuate strip of 60 paper provided with an engageable portion 65 near its end and in its marginal edges, so that the ends may be connected by a form of interlocking pivotal connection which will permit the smaller end of each display device to be opened larger than its normal position and 70 thus passed over the bottle neck flange without damaging or tearing the paper. I have devised such a construction and have found by practice and experience that this construction is more satisfactory than others, that 75 the display device can be manufactured and sold to dealers at comparatively low cost and can be used by the dealers with their individual advertisements thereon so as to advertise their commodities effectively and 80 economically.

The construction which I have devised leaves the bottle neck flange and an adjacent portion of the bottle neck exposed, so 85 that the individual milk bottle may easily be 90

grasped by the hand without engaging the display device on said bottles.

Another object of the invention is to provide an improved display device embodying the construction and arrangement and adaptability above indicated and possessing the advantages hereinafter disclosed, reference now being made to the accompanying drawings, in which—

10 Fig. 1 is a view showing one form of my improved display device before the same is shaped for attachment to a milk bottle.

15 Fig. 2 is a perspective view showing the display device rolled nearly to position for attachment of its ends.

Fig. 3 is a perspective view of the completed device mounted on the neck of a bottle.

20 Fig. 4 is a plan view of an alternative form of a display device having another form of end attaching means.

Fig. 5 is a perspective view showing the display device of Fig. 4 assembled and mounted on a milk bottle.

25 The device shown in Figs. 1, 2 and 3 is obtained by cutting or forming a sheet of material to form a blank 1 having an arcuate outer or lower edge 2 and an arcuate inner or upper edge 3. The blank 1 is preferably of paper or other pliable material having a surface which will readily receive the imprints of advertisements or displays 4.

30 These blanks 1 are made of predetermined lengths, so that when the ends of the blanks are attached together, economical display devices are obtained for application to milk bottles of predetermined sizes. This is to say that for the quart bottles the display devices are made of one size, and are made of another size for the half pint bottles, and may be made 35 of intermediate sizes for the intermediate sizes of bottles.

35 The ends of the blank 1 are constructed so that they may be connected together to form a conical display device having at its upper end an opening 5 (Fig. 3) of approximately the same diameter as the diameter of the flange 6 at the upper end of the tapered bottle neck 7 extending upwardly from the body 8 of the bottle. My invention, in its preferred form, comprises means for connecting the ends of the blanks, so that even if the opening 5 is of slightly less diameter than the diameter of the flange 6, nevertheless the conical display device may be passed downwardly across the flange 6 and onto the bottle neck 7 without tearing or damaging the display device. This desirable and beneficial result is obtained by providing a connection for the ends of the blank, which connection 50 may be termed elastic or pivotal, because it permits enlargement of the opening 5 for the purpose indicated.

55 Near one end of the blank 1 is an approximately radial slit 9 formed wholly between the outer edge 2 and the inner edge 3, so that

60 said slit 9 does not intersect either of said edges. From the opposite end of the blank 1, a slit 10 is cut and is spaced from the inner edge 3 of the blank about the same distance that the inner end of the slit 9 terminates from said edge 3, thereby providing a tongue 11 formed between said slit 10 and the inner edge 3 of the blank. From the outer edge 2 of the blank a slit 12 extends approximately radially toward the slit 10 forming a tongue 13 between said slit 12 and the adjacent end of the blank 1. The inner end of the slit 12 is spaced from the slit 10 a distance approximately equal to but essentially not in excess of the length of the slit 9. This is necessary because the material between the slit 10 and the inner end of the slit 12 must extend and remain extended through the said slit 9 when the device is assembled.

65 When the device is to be used and attached to the milk bottle for which it is intended, it is rolled to approximately conical form in which the end containing the slits 10 and 12 overlaps the end containing the slit 9. The tongue 13 is then passed through the slit 9 and the end of the material containing the slit 12 is then moved downwardly until the material below the lower end of the slit 9 is received in the slit 12, as should be understood by reference to Fig. 3 of the drawings; and, at the same time, the end of the blank below the slit 10 is passed through the slit 9, leaving the tongue 11 overlapping the opposite end of the blank above and beyond the slit 9, all of which is clearly apparent from Fig. 3 of the drawings. Thus, the tongue 13 and the material between the slits 10 and 12 are arranged to extend through the slit 9 and interlock with the material beyond the ends of the slit 9 to provide a pivotal or elastic attachment that will hold the device in truncated conical form and that will permit manipulation of the device in such a way as to enlarge the opening 5, so that the device will not be torn or mutilated even though the flange 6, which is passed through said opening 5, may be of larger diameter than the normal diameter of said opening 5. As shown, the slit 10 extends from the end of the blank 1 at an incline toward the edge 2, so that the outer end of the slit 10 is a greater distance from the edge 2 than is the inner end of said slit 10. Accordingly, when the device is assembled, as described, the tongue 13 and the portion of the material immediately below the slit 10 form elastic or pivotal interlocks beyond the ends of the slit 9. This is true because the tongue 13 extends downwardly below the lower end of the slit 9 and the corner, formed by the intersection of the slit 10 with the end of the blank, extends above the upper end of the slit 9.

total movement of the interengaged parts when the device is closed and slipped over the end of the bottle. Moreover, the tongue 11, which is above the slit 10, is entirely detached 5 from the end of the device against which it lies and this arrangement will permit enlargement of the opening 5, so that the device can easily slip over the end of the bottle. When the device is on the bottle, the lower end of 0 said device is approximately at the beginning of the taper of the bottle and the lower edge of the device is approximately of the same diameter as the diameter of the body 8. Accordingly, the device fits snugly upon the 5 lower end of the tapered portion 7 of the bottle and is supported thereby in such a position as to display the advertisements carried by the device.

The device shown in Figs. 4 and 5 comprises an arcuate blank 14 having a curved lower edge 15 and a curved upper edge 16 cut on a radius of the same length as the lower edge. This device comprises means for obtaining a pivotal connection between 0 the overlapped ends. At one end of said device, a slit is formed, said slit comprising a transverse portion 17 and ends 18 inclining in directions away from the end of the blank and toward the edges 15 and 16, respectively, as clearly shown in Fig. 4. The opposite end of the device is formed with an elongation 19 of less width than the adjacent end of the blank and of greater width than the length of the slit 17, 18. The inner edge of 5 the extension 19 is separated from the end of the blank by a slit or notch 20 and the outer edge of said elongation is separated from the end of the blank by a slit or notch 21. These slits or notches 20 and 21 leave 0 the extension 19 integrally united with the end of the blank by the connecting portion 22. This blank is rolled or shaped into approximately conical form so as to leave an opening 23 at the upper end of the device 5 having a diameter equal to or slightly in excess of the diameter of the flange 24 at the upper end of the bottle to which the device is to be applied. The flange 24 is at the upper end of the tapered neck 25 of the 0 bottle which tapers upwardly from the cylindrical body 26. The ends of the blank are attached together to provide the completed device by extending one of the edges of the extension 19 through the slit 17 and 5 then manipulating the device so that the opposite edge of the extension 19 may be extended through said slit and the lateral edges of the extension 19 caused to engage the inner side of the blank beyond the ends of the 0 slit portion 18. This provides a sort of elastic or pivotal connection that will permit the device to be passed over a bottle neck even though the flange 24 at the upper end of the bottle neck is slightly in excess of the normal 5 diameter of the opening 23. This is true be-

cause the upper edges of the device above the slit 17, 18 are not attached, but can slip relatively so as to permit the device to be passed properly onto a bottle. The blank 14, like the blank 1, is preferably made of paper having a surface that will receive and contain advertisements, such, for instance, as the advertisements 4, or other advertising matter. When this device is on the bottle, the lower edge of the device is at the upper end of the cylindrical portion 26 of the bottle and the device fits snugly and neatly upon the lower end of the tapered portion 25 and thereby displays any and all advertising matter borne by the device.

From the foregoing, it must be apparent that my improved advertising device is intended specially to meet an existing need for the appropriate advertisements in connection with milk bottles and that this desirable result is obtained. Any appropriate advertisements or displays may be formed or displayed upon the outer surfaces of the conical display devices. The smaller end of the conical device is of sufficient size to permit the end and neck of the bottle to pass therethrough but will not permit passage of the larger portion of the bottle beyond the neck thereof. Thus, the device will be supported upon and about the neck of the bottle and constitutes an inexpensive and highly desirable device that may be manufactured at permissible cost and applied without difficulty. The construction and arrangement of the device may be varied otherwise than as specifically described and within the scope of equivalent limits without departure from the nature and principle of the invention. I do not restrict myself unessentially, but what I claim and desire to secure by Letters Patent is:

1. A display device comprising an arcuate piece of pliable material having a slit near one end extending toward opposite edges of said piece of material and having a slit extending from the opposite end and a slit from one edge toward said last named slit, the portion of said material between said two last named slits being arranged to extend through said first slit, and the portion of material between said third slit and the end of the piece of material extending downwardly beyond the lower end of said first slit and forming an interlock holding said material in truncated conical form.

2. A display device comprising an arcuate piece of pliable material having a slit near one end extending toward opposite edges of said piece of material and having a slit extending from the opposite end and a slit from one edge toward said last named slit, and a tongue between said third slit and the end of the piece of material adapted to be passed through said first slit and interlock with said material beyond one end of said first slit to

hold said material in truncated conical form.

3. A display device comprising an arcuate piece of material having a slit near one end extending toward opposite edges of said piece of material and having a slit extending from the opposite end toward the outer edge of said piece of material and a slit from the outer edge of said piece of material toward said last named slit, and a tongue between said last named slit and the end of the piece of material containing said second slit adapted to be passed through said first slit and interlock with said material to hold said material in truncated conical form.

4. A display device for application to a bottle having a cylindrical body portion, a tapered neck portion defining an enlarged mouth, and an enlarged top flange; said device comprising an arcuate piece of pliable material adapted to be formed into a truncated conical member having a lower diameter approximately equal to the diameter of the body portion of the bottle and an upper diameter approximately equal to an intermediate diameter of the tapered neck portion of the bottle, and means for so connecting the ends of said arcuate piece as to hold the same in the form of the truncated conical member and permitting enlargement of the upper diameter of the member.

5. A display device for application to a bottle having a cylindrical body portion, a tapered neck portion defining an enlarged mouth, and an enlarged top flange; said device comprising an arcuate piece of pliable material adapted to be formed into a truncated conical member having a lower diameter approximately equal to the diameter of the body portion of the bottle and an upper diameter approximately equal to an intermediate diameter of the tapered neck portion of the bottle, and means integral with said arcuate piece for so connecting the ends of said arcuate piece as to hold the same in the form of the truncated conical member and permitting enlargement of the upper diameter of the member.

6. A neck band for milk bottles comprising an arc-shaped body having a notch at one end and a tab at the opposite end, said tab having an overhanging shoulder portion and being adapted to be inserted through said notch with the shoulder portion extending beyond the notch to produce a latching operation, said tab being loosely received in said notch so that the smaller end of the band may have its diameter increased when desired.

7. A truncated cone band for milk bottles formed from an arc shaped blank provided with a tab at one end and a notch at the opposite end, the relative shapes of the notch and tab permitting a swinging motion between the respective ends when joined so as to permit an enlargement of the diameter on the small end of the cone.

8. A display device for use on a milk bottle having a cylindrical body and a tapered upper portion comprising an arcuate piece of pliable material in hollow truncated form and having a diameter at its lower end approximately equal to the diameter of the bottle for which the device is intended and having a diameter at its upper end approximately equal to an intermediate portion of the tapered upper end of the bottle for which the device is intended, whereby said device will be supported on the lower end of the tapered portion of the bottle in a position in which the lower edge of said device is approximately at the upper end of the cylindrical body of the bottle, and relatively movable interlocking means connecting the end portions of said piece of material together and permitting enlargement of the upper diameter of the device.

9. A display device for use on a milk bottle having a cylindrical body and a tapered upper portion comprising an arcuate piece of pliable material in hollow truncated form and having a diameter at its lower end approximately equal to the diameter of the bottle for which the device is intended and having a diameter at its upper end approximately equal to an intermediate portion of the tapered upper end of the bottle for which the device is intended, whereby said device will be supported on the lower end of the tapered portion of the bottle in a position in which the lower edge of said device is approximately at the upper end of the cylindrical body of the bottle, and relatively movable interlocking means connecting the end portions of said piece of material together and permitting enlargement of the upper diameter of the device.

10. A display device for use on a milk bottle having a cylindrical body and a tapered upper portion comprising an arcuate piece of pliable material, means pivotally connecting the ends of said piece of material and holding said material in hollow truncated conical form having a diameter at its lower end approximately equal to the diameter of the bottle for which the device is intended and having a diameter at its upper end approximately equal to an intermediate portion of the tapered upper end of the bottle for which the device is intended, said means permitting the open upper end of said device to expand when the device is passed over the upper end of the milk bottle.

11. A display device comprising a flat section of pliable material having its upper and lower edges curving, said flat section being adapted to be rolled into tapered form with its ends overlapping and having the upper and lower edges respectively of the overlapping portions of said ends approximately even with each other, and means integral with one end interlocking with the other end of said section and pivotally connecting said overlapping ends in said relationship, whereby the smaller end of the device may enlarge to permit said device to be passed onto a support.
